VENETIAN BLIND

William Wade, Chicago, and Edwin North, Rockford, Ill., assignors to National Lock Company, Rockford, Ill., a corporation of Delaware

Application January 28, 1937, Serial No. 122,795

7 Claims. (Cl. 156—17)

This invention relates to Venetian blinds and especially to means for attaching the blind slats to their suspending elements.

Particularly stated, it is an important object 5 of the invention to provide an improved means for attaching blind slats to supporting chains in the so-called chain-tape type of blind.

A further object is the provision of a clip 10 having formations engageable with a blind slat for removable attachment to the same, and having an attaching loop supportably and pivotally 15 engaging a suspending chain and at the same time guiding a different or operating chain from the top to the bottom of the blind.

Other novel features of the invention will appear as the following detailed description proceeds in view of the drawing, in which:

Fig. 1 is a fragmentary front elevation of a 20 chain-tape Venetian blind utilizing the novel clip means;

Fig. 2 is an enlarged perspective of a clip, chains, and fragment of a slat;

Fig. 3 is an enlarged vertical section taken on lines 3—3 of Fig. 1;

Fig. 4 is an enlarged bottom plan of the clip, engaged with a slat and having the chains in section, the view being taken along lines 4—4 of Fig. 3; while

Fig. 5 is a bottom perspective view of a modified form of the clip.

In applicants' co-pending application Serial No. 122,793, filed January 28, 1937, a chain-tape type of Venetian blind is described in detail, such blind being shown in part in Fig. 1 herein.

The blind includes a plurality of slats 10 suspended in spaced relation from a carriage 12 by means of chains or like flexible members 14, the carriage being extended between brackets, such as bracket 16, which are secured in the upper corner portions of a window casing 18.

In the type of blind described in our co-pending case mentioned above, the flexible supporting and control elements or chains are provided in pairs on opposite sides of the slats. Such a pair is illustrated herein in Figs. 2 and 3 and includes a front chain 14, which is in fact a supporting chain since it is attached to each of the slats, and a rear or inner chain 14', which may be called a control chain for convenience.

At their respective lowermost ends 15 and 15', 50 each of the chains 14 and 14' is connected to the lowermost slat 11 by a cleat 17. The chains 14 pass over roller means 13 in carriage 12 and into a pivoted roller housing 20 from which they issue 55 to connect with a common pull-chain 22.

The means for attaching chains 14 to each of the slats 10 is the clip and link shown in perspective in Fig. 2.

The clip comprises an elongated resilient metal strip bent back upon itself in substantial U-shape 5 to form the clip member, the upper longitudinal end portion of which is bent outwardly to provide a lip 28, while the body portion of the strip near the lower longitudinal extremity of the strip is crimped inwardly to provide a locking hump 28. 10 The end of the clip adjacent hump 28 is bent out slightly to provide a lower lip 30.

As seen in Fig. 4, the link comprises a looped wire 32 passed through the bight portion 34 of clip 24 and having its free end portions 36 passed 15 through the open part of one of the links of chain 14 and thereafter bent back upon themselves, thus securing the link 32 to chains 14.

Each of the slats 10 is provided in its bottom portion with a slot 40 dimensioned generally to receive the locking hump 28 of clip 24 and prevent the casual removal of the latter from the slat when the clips are attached to their respective slats as seen in Figs. 3 and 4.

The resiliency of the stock from which clips 24 25 are stamped or formed is adequate to urge the respective clip portions and lips 28 and 30 toward each other, and in applying the clip and its link or loop 32 to a slat 10, the clip and lips 28—30 30 thereof are urged against the edge of the slat at 35 a point opposite a slot 40, whereupon the sides and lips of the clip spread and the same slides readily onto the slat with the hump 28 snapping into its slot 40. Thereafter the clip cannot be 40 accidentally disengaged from the slat, but can be 45 removed only by bending the lower arm of the clip to move the hump 28 out of its slot or depression 40.

It is to be observed that the inner chains 14' are not attached to each slat 10, but only to the 40 lower slat 11 and at their upper ends to the carriage 12. However, the links 32 are dimensioned to have their loop portions 32' adequately wide to receive the inner chains 14', the latter passing through each loop portion 32' of each link 32 45 as they extend from the bottom slat 11 up to the carriage 12. Thus the inner chains 14' are guided between the bight portion 34 of a clip and the flared free ends of the link 32 in the loop portion 32' thereof.

The reason for the foregoing arrangement is that the carriage 12 is adapted to pivot about its long axis between its brackets 16 by manually operable means described in our application mentioned above, and in so doing the chains 14, 55

being each attached to the edge of each slat 10, rise on one side of the carriage and descend on the opposite side corresponding to the pivot of the carriage and the movement of its side edge portions. This movement of chains 14 likewise causes one side (edge) of each slat 10 to rise and the opposite side (edge) to fall, and the several slats therefore pivot about their respective long axis and open and close like a louver type shutter. 10 Operation of the pull-chain 22 will result in the raising of chains 14' which are attached to the bottommost slat 11, while chains 14 tend to remain stationary, so that inner chains 14' move freely upward guided within loops 32' of links 32. 15 This ultimately effects a lifting of slat 11 against the intermediate slats 10 and nests the latter upwardly in a direction against the carriage, corresponding to a raising of the blind.

The modified form of clip seen in Fig. 5 comprises a wire-like member bent back upon itself to form a first or end bight portion 45. Between this bight 45 and the free ends of the wire a second or intermediate bend or bight 46 is formed in both side extensions provided by the formation 25 of the first bend, and the latter being in a plane at substantially right angles to the planes of the second bight formations.

The wire is thus formed into a hook having an end 45, an intermediate bight 46 and spaced side 30 extensions 47 each having their outermost or endmost extremities bent back upon themselves to form attaching hooks or claws 48.

In use, the modified clip is attached to a slat 10 having spaced openings generally indicated 35 at 49 formed therein adjacent its longitudinal edge portions.

By making the clip of spring stock, the pre-formed hook portions 48 may be guided into holes 49 so that the hook or bight portion 45 closely overlies or presses against a face of the slat 10 as shown in Fig. 5, whereupon one of the attaching loops 32 may be slipped between the bight part 45 of the clip and the slat so as to lie between the intermediate bight portions 46 45 and the edge of the slat.

When the wire stock is not springy, the endmost portions of the hook ends 48 of the clip may be bent over onto the face of the slat after they are inserted in holes 49 therein.

It will therefore appear that we have provided a simple yet rugged and highly useful clip means for blind structures, and while we have described a preferred form of the clip for purposes of illustration, the simple device may be variously 55 formed and modified without departing from the spirit and intent of the invention, and we do not intend to be limited to the precise details recited but desire to avail ourselves of all variations, modifications, and combinations of the invention, 60 as defined in the appended claims.

Having thus described our invention, what we claim as new and desire to protect by Letters Patent is:

1. A clip comprising a U-shaped member constructed of springy material and having lip portions formed at its free ends and an inwardly directed hump formed adjacent one lip portion, together with an attaching member mounted in the bight portion of the clip, said attaching member being attached to supporting means and said clip being engaged with a supported member, said supported member having a recess in which said hump is disposed whereby to provide a releasable detent means for securing the clip and 75 supported member in engagement as aforesaid.

2. Slat-engaging means for Venetian blinds of the type including slat-supporting chains, said means comprising a U-shaped clip having free end portions bent outwardly to form lips, said clip being slid onto the edge of a slat for supporting engagement therewith, said clip further having an inwardly projected part constituting a detent disposed between the bight portion and one of said lips in a leg of the U, together with a chain-engaging link in the form of a loop passing around the bight portion of the clip and having free end portions extended through a link in one of said supporting chains for attachment of the loop and clip to the latter, said slat having a formation in which said detent is received when 15 said clip and slat are in assembled relation.

3. In Venetian blinds having slats supportably attached to flexible members, slat attaching means comprising a clip in the form of an elongated body member bent back in a direction 20 upon itself and having its free end portions flared outwardly to form lips and having an inwardly directed hump formed near a said lip, said slats having hump-receiving slots formed near an edge thereof and said clips being fitted over a said edge onto said slat with the said hump urged into a said hump-receiving slot, said clip being attached to a said flexible element by means of a wire-like link looped around the bight portion of said clip and having free end portions passed 30 through said flexible element and bent back upon themselves to prevent disengagement from the flexible member.

4. In blinds having movable slats and elongated flexible elements in pairs for support and movement control of said slats, slat attaching means comprising a clip in the form of an elongated flexible body bent back upon itself and having a hump formed near one peen end portion, said slats having hump-receiving slots formed therein near an edge portion thereof, said clips being fitted over said edge portion onto said slat and said hump being engaged with said hump-receiving formation, said clip being attached to one of said pair of flexible elements by means of a wire-like link looped around the main body bend of said clip and having free end portions passed through said flexible element so as to leave an open eye portion between said clip and said flexible element, said free end portions last-mentioned being bent to prevent disengagement of said link from said flexible element, and the other flexible element of said pair being passed through said open eye portion.

5. A supporting clip for attaching a Venetian blind slat to supporting elements, said clip comprising a wire bent back upon itself in U-shape to form an end bight, and again bent back upon itself in the form of a hook with an intermediate bight between said end bight and the free end portions thereof, said free end portions being inserted through said slat adjacent a longitudinal edge thereof and bent over onto the slat to prevent removal therefrom, with the said intermediate bight portion of said hook formation spaced from said edge of the slat to receive an attaching loop member, and said clip having its end bight closely overlying the surface of said slat onto which said free end portions are bent.

6. Attaching means for mounting a slat between spaced flexible slat supporting elements in Venetian blinds and the like, said means comprising a substantially U-shaped clip of springy material having oppositely disposed free end portions curved divergently to provide engaging 70 75

5 lips adapted to slide onto the edge portion of a slat, one arm of said clip having an inwardly extending hump placed substantially close to the lip portion on said arm, said slat being provided with slightly recessed formations adjacent an edge portion thereof and said clip being forced onto said slat over said edge portion, the aforesaid hump portion of each clip being firmly engaged in one of said recessed portions in the slat,
10 whereby said clips are secured against accidental dislodgement, and loop means passed through the bight portion of each of said clips and attached to one of the flexible mounting elements for the purpose aforesaid.

15 7. In a Venetian blind of the type including slat-supporting members and a plurality of slats, clip means for removably attaching said slats to

said supporting means, said clip means comprising: a U-shaped clip member of springy material having outwardly flared lips at the end of the legs of the U and there being provided an inwardly directed part in one of the legs between the lip and the bight portion of the clip and constituting a detent, said clip being attached to said slats with the lip portion thereof fitted onto the edges of the slats, and each of said slats having a detent-receiving notch formed therein adjacent the edges thereof onto which the clip are fitted and into which one of said detent formations is received when the clip is attached as aforesaid, and means for attaching said clips to said supporting means.
